CLAIM

The ornamental design for a knife block as shown and described.

DESCRIPTION

FIG. 1 is a front, right side, top perspective view of a knife block showing my new design;

FIG. 2 is a rear, right side, bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a front, right side, top perspective view thereof with the front half of the knife block separated from the rear half of the knife block.

The broken lines depict portions of the knife block that form no part of the claimed design.

1 Claim, 9 Drawing Sheets
